Filed Jan. 9, 1963, Ser. No. 73,100

Term of patent 14 years

(Cl. D13—1)

FIG. 1 is a perspective view of a single panel of the panel unit shown in FIGURE 2.

FIG. 2 is a perspective view of a panel unit showing our new design, the broken line showing of the door frame being disclosed for illustrative purposes only.

FIG. 3 is a sectional view taken on line 3—3 of FIG. 2.

FIG. 4 is a fragmentary enlarged view showing a portion of the panels of our design in greater detail.

FIG. 5 is a sectional view taken on line 5—5 of FIG. 4.

FIG. 6 is a view taken along line 6—6 of FIGURE 1.

The characteristic features of the design reside in the surface ornamentation. The rear of the unit is plain.

We claim:

The ornamental design for a panel unit, as shown and described.
